UNITED STATES PATENT OFFICE.

BENJAMIN F. GRAY AND ANDREW J. MORRISON, OF VALERA, TEXAS.

SAFETY DEVICE FOR BANK VAULTS.

Application filed December 6, 1921. Serial No. 520,328.

To all whom it may concern:

Be it known that we, BENJAMIN F. GRAY and ANDREW J. MORRISON, citizens of the United States, residing at Valera, in the

5 county of Coleman and State of Texas, have invented new and useful Improvements in Safety Devices for Bank Vaults, of which the following is a specification.

Our present invention has reference to a 10 safety device for bank vaults and is in the nature of a means for preventing the throwing of the locking bars, and consequently preventing the operation of the combination lock except by authorized persons.

15 Our improvement is devised for preventing bank employees from being forcibly locked inside of the bank vault, and in carrying out our invention it is our aim to arrange in the casing for the vault door spring 20 influenced slidable means which normally cover the openings therein that receive the lock bolts, so that the said bolts cannot be "shot" or thrown until the said obstructing means is manually operated to bring 25 the same to non-bolt obstructing positions.

It is also our purpose to produce a means 30 for preventing bank employees from being accidentally or intentionally locked in a bank vault that comprise spring influenced 35 notched members arranged for slidable movement in the casing to positions to obstruct the passage of the bolts through the openings in the casing provided therefor, and said members being movable by a key and held 40 in a position whereby the notches thereof will be arranged opposite the bolt receiving openings whereby, when the bolts are thrown to locking position, the same will contact with the notched portions of the said members to swing the same to bring the said 45 members out of engagement with the means that hold the same in retracted position, so that when the vault door is again opened the members will be automatically rear ranged in bolt obstructing position.

We accomplish the foregoing and other 50 objects which will appear as the nature of the invention is better understood, by a construction, combination and operative association of parts, such as is disclosed by the drawings which accompany and which form part of this specification.

In the drawings:

Figure 1 is a transverse sectional view 55 through a bank vault with the door open.

Figure 2 is an enlarged fragmentary ele-

vation with parts broken away and parts in section and showing the obstructing members in the path of contact with the bolts of the door to prevent locking the door.

60

Figure 3 is a similar view but showing the door closed and locked.

Figure 4 is a fragmentary sectional view illustrating the manner in which the spring influences the bolt obstructing member to 65 bolt obstructing position, the bolt being illustrated by the dotted lines.

Figure 5 is a view illustrating the manner in which the key is employed for operating 70 the bolt obstructing member.

70

Figure 6 is a view of the key.

Referring now to the drawings in detail, the numeral 1 designates a bank vault, 2 the stepped portions at the opening which provides the door casing, and 3 the door. In 75 the showing of the drawings, we have illustrated only one door, but as is common in bank vault constructions, the same are usually provided with two doors, and it will be apparent as the description progresses that 80 the improvement is equally effective on one or two doors.

On the stepped portion of the door casing that is provided with the openings for the bolts 4 which are slidable through the 85 stepped edge of the door, we secure in any desired or preferred manner our improvement. The casing of our improvement may be let in slots in the door casing, or may be simply screwed to the stepped portion there of. Our improvement is designed for use upon different sized door casings, and therefore the casing or housing 5 of our device is constructed of two sections which are tele scopically or slidably associated and which 95 have slidable means for holding the sections properly adjusted on each other. The housing 5 is substantially rectangular in cross section.

The outer face 8 of the housing is provided 100 with openings 9 respectively which are ar ranged to receive therethrough the bolts 4 when the said bolts are operated to lock the door 3 in the casing. At a suitable distance from one end of each of the openings 9 the outer or face plate 8 of the housing 5 has on its inner surface an inwardly extended lug 10.

Arranged for slidable movement in the 105 housing are block-like bolt obstructing mem bers 11 respectively. Each of these mem bers is influenced by a spring 13 to bring

110

the same in a position to cover the opening 9, and thus prevent the entrance of the bolts 4 through the said openings. Each of the members 11 has one of its corners notched, as at 14 and is provided with a transversely arranged elongated slot 15. Through the sides of the housing 5 and through the slots 15 of the obstructing members there are guide members or pins 16.

10 The outer face of the housing, from the opposed end walls provided by the bolt openings 9 are slotted, as at 17 for the reception of the bit end 18 of a key 19. The key, when inserted in one of the slots can be brought to engage with the inner wall provided by the notch 14 to move the member 11 against the influence of the spring 13 and by virtue of the contact of one of the walls of the slots 15 with the guide members 16,

15 the shoulder of the said member will be brought to engage with the lug 10, thus holding the body of the member away from obstructing position with respect to the opening 9, but at the same time arranging

20 the wall 20 provided by the notch 14 in a position to be contacted by the bolt 4 of the door 3. When the members 11 are in such position, the bolts 4 may be "shot" to locking position. When in such position, the bolts

25 will contact with the walls 20 and tilt each of the members 11 sufficient to bring the shoulders 21 which provide the inner walls of the notches 14 above or out of engagement with the lugs 10, and allow the springs 13 to throw or longitudinally move the bolt obstructing members 11 to bolt obstructing position when the bolts have been retracted and the door opened.

It will, of course, be obvious to those skilled in the art to which this invention relates that the combination lock of a bank door cannot be operated until the bolts are thrown to locking position, and therefore it will be impossible for a bank robber to force a clerk into a vault and to lock him therein unless he is acquainted with the construction and operation of our improvement. Even with such knowledge, it would require the use of the key for the proper operation of the obstructing members 11, and these keys are designed to be carried by only authorized persons in the bank. It is also thought that the foregoing description, when taken in connection with the drawings will fully set forth the construction, operation and advantages of the improvement and that further detailed description will not be required.

Having described the invention, we claim:

1. In combination with a bank vault, of

means for preventing the accidental throwing of the bolts on the door in locking position in the casing for the door, comprising a housing constructed of adjustable sections secured on the casing and having openings to receive the bolts therethrough, spring influenced notched members in the housing susceptible of a longitudinal and tilting movement and normally covering the bolt receiving openings, means for moving the members out of such position to bring the notched ends thereof opposite the openings in the housing, means sustaining the members in such position, and the notched portions of the members designed to be contacted by the thrown bolts to swing the said members away from the sustaining means therefor.

2. In combination with a bank vault, of means for preventing the accidental throwing of the bolts of the door which enter the casing for the door, comprising an adjustable housing secured in the casing and having openings in a line with the bolts, said housing being slotted from the opposed end walls provided by the openings, notched block-like members in the housing, spring means influencing the members to bring the same over the openings, said members having transverse elongated slots, guide means arranged transversely through the housing and received in the slots, lugs in the casing, means, comprising a key designed to have its bit inserted through the slots to engage with the members to move the same against the pressure of their springs to cause the shoulders provided by the notches of the said members to be engaged by the lugs and for retaining the notched portions of the members opposite the openings, and said portions of said members designed to be contacted by the bolts of the door when the said bolts are thrown to swing the members to bring the same out of engagement with the lugs.

3. The combination with a safe having a hinged door and a sliding lock bolt, of an open position lock comprising a casing and a vertically movable lock-bolt-intercepting plunger mounted therein and arranged to be forced up into said casing out of the path of movement of said lock bolt but to drop into the path of movement of said lock bolt and thereby prevent said lock bolt from being forced to a door-locking position.

In testimony whereof we affix our signatures.

BENJAMIN F. GRAY.
ANDREW J. MORRISSON.
